CLAIM

The design for a cellphone bracket to connect riflescope substantially, as shown and described.

DESCRIPTION

FIG. 1 is a front elevational view of the present cellphone bracket;

FIG. 2 is a rear elevational view of the present cellphone bracket;

FIG. 3 is a right side elevational view of the present cellphone bracket;

FIG. 4 is a left side elevational view of the present cellphone bracket;

FIG. 5 is a top plane view thereof;

FIG. 6 is a bottom plane view thereof;

FIG. 7 is a front isometric view thereof;

FIG. 8 is a rear isometric view thereof;

FIG. 9 is an further front isometric view thereof; and,

FIG. 10 is a further rear isometric view thereof.
